UNITED STATES PATENT OFFICE

133,268

DESIGN FOR A PROJECTION MACHINE

Worthy L. Chambers, Chicago, Ill., assignor to
Novex Corporation, Chicago, Ill., a corporation
of Illinois

Application February 4, 1942, Serial No. 105,639

Term of patent 14 years

To all whom it may concern:

Be it known that I, Worthy L. Chambers, a citizen of the United States, residing in the city of Chicago, county of Cook, and State of Illinois, have invented a new, original, and ornamental Design for a Projection Machine, of which the following is a specification, reference being had to the accompanying drawings forming a part hereof.

In the drawings:

Fig. 1 is a side elevational view of a projection machine showing my new design.

Fig. 2 is a top plan view.

Fig. 3 is a rear elevational view.

Fig. 4 is a front elevational view.

Fig. 5 is a side elevational view of the machine with the projector housing in tilted position for projection upon a screen at the rear end of the machine.

I claim:

The ornamental design for a projection machine, substantially as shown and described.

WORTHY L. CHAMBERS.
